UNITED STATES PATENT OFFICE.

WILLIAM MARTIN, OF PHILADELPHIA, PENNSYLVANIA, ASSIGNOR TO
THOMAS DOLAN AND R. WILLIAMS, JR., OF SAME PLACE.

DESIGN FOR STOCKING FABRIC.

Specification forming part of Design No. 7,963, dated December 29, 1874; application filed August 19, 1874.
[Term of Patent 3½ years.]

CASE A.

To all whom it may concern:

Be it known that I, WILLIAM MARTIN, of Philadelphia, Pennsylvania, have invented a Design for a Stocking Fabric, of which the following is a specification:

In the accompanying drawing, Figure 1 is a diagram illustrating the shape of the outline of the stripes of which the pattern is composed, and Fig. 2 is a view of the complete design, the remainder of the pattern being merely a repetition of that which appears.

Each of the stripes is partly straight and partly zigzag, as plainly shown in the diagram, and a peculiar and pleasing effect is produced in the complete design by arranging the zigzag portions of the several strips directly opposite each other, as shown in Fig. 2. The pattern is composed of parallel stripes

A, B, and C, the former of which has a narrow edging, a, at its opposite sides, while the stripe B is composed of a number of minor stripes, bars, or ribs blended into each other, as shown. The stripes C are simple narrow ribs of one shade or color.

Irrespective of the colors employed, I claim—

The design for a stocking fabric, consisting of stripes A B C parallel to each other, each stripe being partly straight and partly zigzag, as set forth.

In testimony whereof I have signed my name to this specification in the presence of two subscribing witnesses.

WM. MARTIN.
